UNITED STATES PATENT OFFICE.

PENROSE E. CHAPMAN, OF ST. LOUIS, MISSOURI.

ARMATURE-WINDING MACHINE.

No. 874,163.

Specification of Letters Patent.

Patented Dec. 17, 1907.

Application filed August 15, 1904. Serial No. 220,886.

To all whom it may concern:

Be it known that I, PENROSE E. CHAPMAN, a citizen of the United States, residing at the city of St. Louis, State of Missouri, have invented certain new and useful Improvements in Armature-Winding Machines, of which the following is a full, clear, and concise description, reference being had to the accompanying drawings, forming part hereof.

My invention relates to drum armature winding machines in which the wire is wound directly in slots in the surface of the core, and consists in the novel combination and arrangements of parts as will be more fully hereinafter described and claimed.

The object of my invention is to construct an improved armature winding machine, by which the conductors may be directly wound on the core of the armature, and in the slots or openings provided for the same, without the necessity of doing so by hand or of first forming the coils and placing them on the core afterwards usually by hand, thereby greatly expediting the operations especially in armatures having a large number of poles, wherein hand winding is difficult or impossible.

With this object in view my invention consists of a machine for winding drum armatures, which comprises means for rotating the armature in a plane parallel to its shaft, means for holding said armature to be wound in proper relation to other portions of the machine, means for holding a wire directing saddle with its stationary and adjustable coil forming guides, said saddle being adapted to rotate with the armature, a perforated finger for guiding the coil forming wire to said coil forming saddle and guides, means for throwing said finger back out of the way, means for flexibly mounting said saddle, that it may follow irregularities in the movement and contour of said armature, means for automatically restoring said saddle to its normal position when released, means for engaging and disengaging this saddle from the work, means for controlling rotation of the work, means for applying a tension to the coil forming wire, means for recording automatically the number of turns wound, and in the arrangement and shape of said saddle and guides.

My invention consists in certain details, combination, and shape of parts which will

be more fully hereinafter described and claimed.

The action, operation, and construction, of my invention will be better understood by referring to the results that would be obtained were one to try and wind wire or string diametrically upon the outside of the flared or larger portion of a funnel, as the wire or string would inevitably slip towards the smaller end of said funnel. It will be seen further that upon continuing to wind, the wire or string would be forced towards and upon the spout and accumulate thereon, or on any other object which might be substituted therefor, and it is further obvious that said funnel may be of an irregular shape so long as it retains sufficient taper upon some portion or parts to compel the slipping of the wire from the larger to the smaller portion. It is therefore obvious that by altering the shape of said funnel and arranging its smaller end to fit irregular shaped articles in lieu of a spout the device can readily be made to wind or deposit wire &c. upon said articles. In my invention I utilize this action for the winding of armatures, and more especially those requiring the wire to be wound upon a chord of the circle, as is always the case with multipolar drum armatures.

Throughout these specifications and claims, that portion of the machine having the "funnel" characteristic is referred to as the "saddle".

Having thus described the basic principle of my invention—in the drawings, Figure 1 is a general elevation of the machine with supporting framework removed for the sake of clearness as well as a portion of the saddle removed to show ball and socket mounting on the elastic stem, the conical leveling spring also showing. Fig. 2 is a perspective of the saddle, shown immediately above and slightly removed from a 6 pole armature, partly wound, the last coil being shown immediately below the saddle, completed, and disengaged therefrom.

Similar marks of reference indicate corresponding parts.

Referring to the drawings, 1 is the saddle carrying the stationary wire directing guides 2 of which there are four one at each corner and of which they form a part, and the automatically adjustable directing and forming guides 3 each with its operating springs and

guiding studs 5, and the manually adjustable directing guide 6 with its locking springs 7. A ball and socket joint enabling said saddle to adjust itself to irregularities is shown at 5 8, and 9 is a conical spring for automatically returning the saddle to its normal plane.

10 is an elastic stem carrying the ball to which the saddle is connected, said stem being rigidly secured at its upper extremity 10 to a supporting device, as a taper plug 11 adapted to the tail-stock of a lathe or other support, said plug having a larger opening at its lower end allowing the stem to spring but not too far.

15 12 is a lever adapted to disengage the saddle from the armature and permitting its rotation around the axis, said lever being connected to pedal 14 by means of connecting rod 13 and being returned to normal 20 position by spring 12. An armature is shown at 15 and its commutator at 16.

17 is a perforated finger or guide through which the coil forming wire *a* passes to and over the saddle and its guides into the slots 25 intended for its reception. The tension device 18 is for applying an even tension to the wire *a*.

19 is a hand-wheel for convenience in operation, with the armature supported 30 from the same by means of the uprights 20 and 21-21 being enlarged to form a counter-balance for the commutator or other unbalancing effects.

22 is a pulley for driving, with a clutch 23 35 contained therein, said clutch being attached to the main shaft by means of the key 24 and adapted to operate longitudinally and actuated by the pedal 26 through the connecting rod 25 within the main shaft 34 and the 40 slip collars 27.

22 The saddle 1 is proportioned to fit over the requisite section of the armature, said 45 section representing the spout of the funnel as described hereinbefore. In the preferred 50 form the saddle has its ends beveled outwardly from the armature corresponding to the taper of the funnel, the sides *g* parallel to each other and whose edges exactly register with slots 28 in the armature 15, said 55 beveled ends carrying the coil forming wire downwardly over the predetermined section of the armature core in a substantially similar manner to the action of the funnel hereinbefore described. To insure the wire being carried fairly into the slots 28 the beveled 60 ends of the saddle 1 are extended at the corners to form horns 2, of which there are four, whose function is simply to guide the coil forming wire well within said slots.

60 As it is desirable that one side of some of the coils be wound in the bottom of the slots, I have added a manually adjustable set of horns or guides 6 yoked together in the form of an inverted **U** having ends suitably beveled 65 and adapted to be lowered or raised and held

in either position by springs 7 engaging suitable notches, said guide 6 in the lower position forcing the coil forming wire to or near to the bottom of said slot 28, and in the upper position allowing the wire to drop in the 70 top of said slot co-acting with horn 2.

In order that the ends of the coils shall be of proper shape to fit or "nest" one with the other I have added the coil forming guide 3 centrally located, said guide being mounted 75 loosely within slots cut in the ends of the saddle 1 and adapted to move perpendicularly to the plane of rotation, and studs pass through holes in the yoke of said guides 3 and through the springs 5 which are retained 80 by said studs and press against the yoke of said guide 3, thus allowing it to move but always under tension of said springs 5. Upon the ends of guide 3 are arranged coil-forming surfaces *f* which being parallel or 85 nearly so tend to retain the coil-forming wire *a* after sliding down the beveled surface *s* of said guide 3. The ends of the coil-forming surfaces *f* are pressed by the springs 5 against the winding previously formed; or 90 at the start a small block is placed under them so that none of the coil-forming wire may be crowded off them as it accumulates. At the completion of the coil the entire saddle, guides and all, is raised by pedal 14 95 provided therefor. Guides or stops 29 are provided for compelling registry of saddle sides *g* with slots 28.

A guiding finger 17 having holes in its tip for the passage of the coil-forming wire is 100 arranged to guide said wire directly upon the saddle at a suitable place, and said finger is flexibly mounted that it may be thrown back out of the way.

A revolution counter is shown at 30 operated by its shaft 31 and sprocket wheels and chain 32.

33 is one of the main bearings supporting main shaft 34.

The machine is operated as follows: The 110 armature to be wound is secured in its carrier through supports 20 and 21, saddle 1 lowered over section desired by releasing pedal 14, stops 29 compelling registry of sides *g* with slot edges 28, the wire or wires *a* 115 are threaded through tension device 18 and guiding finger 17 and to the commutator which should now be on the left and secured thereto or to some other fastening, when clutch 23 is actuated through pedal 26 and 120 the whole is thereby rotated to the left. The coil forming wire is thus drawn over side of saddle *g* and down into slot by guide 6 and dropped, next down by guiding surface *s* to retaining surface *f* of adjustable guide 3 and 125 retained there, and the beveled ends of the saddle carry it down to horns 2, with the same operations completed in reverse order on other end of saddle, till the revolution counter 30 indicates proper number of turns, 130

when clutch is released, ends of wire secured, saddle raised with pedal 14, armature rotated on its own axis to new position, and operations repeated till completely wound. 5
ever when winding the last coils it will be found that the last few slots are partially occupied with the first coils, the guide 6 is then raised to its upper limits, spring 7 retaining it there, when it will fill the top of 10 slots as it formerly did the bottom.

I am aware that my invention may take many other forms than that described; for the sake of clearness one only is given, and for like reason and because they form no part 15 of my invention the details of the supporting lathe are also omitted.

What I wish to claim is,

1. In an armature winding machine, the combination with means for supporting an 20 armature in position for winding, of wire directing guides whose directing surfaces are placed at an angle suited to direct coil forming wire within slots in said armature, means for supporting said guides in suitable relation 25 thereto, and means for adjusting said guides relatively to said supports and said armature.

2. In an armature winding machine, the combination of means for supporting and 30 rotating an armature in the plane of its shaft, with a saddle having ends beveled outwardly and away from the armature core, with sides having edges registering with inner edges of 35 slots, gages or stops for compelling said registry with edges of slots receiving coil forming wire, substantially as described.

3. In an armature winding machine, the combination of means for supporting and rotating an armature in the plane of its shaft, 40 with a saddle having beveled ends and sides registering with slots in said armature core, stops for compelling said registry, and guides adapted to carry coil forming wire into slots, said guides being beveled on their outward 45 surface in such manner that coil forming wire will slip over them into the slots, substantially as described.

4. In an armature winding machine, the combination of means for supporting and 50 rotating an armature in the plane of its shaft,

with a saddle having beveled ends, sides registering with slots, stops for compelling said registry, guides for depositing wire within said slots, and adjustable guides for depositing said wire at proper and independent 55 depths within said slots, means for retaining said adjustable guides in place, said adjustable guides and retainers being mounted on said saddle, substantially as described.

5. In an armature winding machine, the combination of means for supporting and rotating an armature in the plane of its shaft, with a saddle having beveled ends, sides registering with slots, stops compelling registry, guides for depositing wire within said slots, 65 adjustable guides for depositing wire at different depths, retainers for said guides, and adjustable guides for carrying wire to its seat, said adjustable guides having a portion of 70 their lower ends arranged to retain coil forming wire, said coil receiving part of its shape by means of said retaining surface, said guide being automatically adjustable to follow the surface of the winding already in place to form its coil directly against previously 75 wound coils, said automatic adjustment being effected by means of springs forcing said guide against the winding previously formed, said guide and springs being carried upon said saddle, substantially as described. 80

6. In an armature winding machine, the combination with means for supporting and rotating an armature in the plane of its shaft, with a saddle having beveled ends, sides registering with slots, stops compelling registry, 85 guides for depositing said wire at independent depths within said slots, automatically adjustable coil forming guides, of means for rotatably, adjustably, flexibly, and removably mounting said saddle and appurte- 90 nances attached thereto upon and with reference to supporting framework, and means for automatically returning said saddle to its normal position when deflected, substantially as described.
